CLAIM

The ornamental design for a treatment applicator, as shown and described.

DESCRIPTION

FIG. 1 is an isometric view of the treatment applicator;
FIG. 2 is a top view of the treatment applicator;
FIG. 3 is a bottom view of the treatment applicator;
FIG. 4 is a left view of the treatment applicator;
FIG. 5 is a right view of the treatment applicator;
FIG. 6 is a back view of the treatment applicator;
FIG. 7 is a front view of the treatment applicator; and,
FIG. 8 is another isometric view of the treatment applicator.
The dashed lines are for the purpose of illustrating environmental subject matter that forms no part of the claimed design.
